HENRY H. BAILEY, OF CHICAGO, ILLINOIS, ASSIGNOR TO THE BARRETT COMPANY, OF NEW YORK, N. Y., A CORPORATION OF NEW JERSEY

DISTILLATION OF TAR AND PRODUCTION OF COKE

Application filed June 29, 1929. Serial No. 374,800.

This invention relates to the distillation of tar, pitch or other residuum and the production therefrom of distillates and coke, and includes an improved method of distillation and improvements in apparatus therefor.

More particularly, the invention comprises a process of distilling tar, etc. in a by-product coke oven after coke has formed in the oven, with introduction of the tar etc. into the coke oven during the later period of the coking operation whereby the tar is distilled and a coke residue produced, the tar oils being taken off through a separate main and separately condensed and the coke residue from the distillation remaining in the coke oven as part of the coke product.

In the operation of by-product coke oven plants a battery or block of ovens is operated as a unit, the individual ovens being charged in rotation at regular time intervals. The coking operation requires a considerable period of time, varying somewhat with the type and construction of the oven, the character of coke produced, the operating schedule, etc. The coking operation in the individual ovens may require, for example, from twelve to twenty hours more or less. The ovens are heated by heating flues so arranged as to heat the oven and the charge therein to the necessary coking temperature. At the end of the coking operation the incandescent coke is pushed from the oven and a fresh charge of coal charged into the incandescent oven. During the early portion of the coking period a relatively large amount of gases is given off and the gases are "rich" in tar constituents. During the later portion of the coking period the volume of gas given off from the charge is much less and the gases are commonly referred to as "lean" gases, being relatively low in tar constituents.

The tar produced at by-product coke oven plants is commonly shipped to tar distillation plants to be there distilled to produce merchantable distillates and pitch residues. The pitch residues may be further distilled in a coke still or oven to produce coke there-

from. The distillation to produce pitch, and the coking of the pitch, are usually carried out as separate operations.

The present invention provides an improved process in which the distillation of tar, pitch or residuum and the production of coke and of distillate therefrom is carried out in a single operation at a by-product coke oven plant with utilization of the coke oven itself for the distillation. The transportation of the tar to a tar distillation plant is eliminated and the provision of a separate tar still at the coke oven plant is obviated. The distillation is carried out with existing equipment except for the provision where necessary of a separate vapor main and condensing system for drawing off and condensing the vapors and admixed gases from the distillation. The distillation of tar, moreover, can be carried out without the intermediate production of pitch so that only distillate oil, coke and gas are produced. By collecting the tar at the coke oven plant and returning it and distilling it in the coke ovens, according to the present invention, the entire coke oven plant can be operated, or can in part be operated, so that the tar is utilized and coke, distillate and gas produced therefrom, making unnecessary the sale or shipment or transportation of tar to a tar distillation plant or the provision of separate tar stills or of separate coke stills and eliminating the problem of pitch disposition.

In carrying out the present invention, the coke oven operation is carried out in the usual way during the early portion of the coking period. During a later portion of the coking period, preferably near the end of the coking period, tar is introduced into the top of the coke oven with resulting distillation of the tar and the production of distillate oil, gas and coke. The gases produced by the coke oven during the period of tar distillation are drawn off through a separate main which will permit their collection separately from the normal gases given off from the other ovens. That is, the gases given off from the ovens during the early portion of the coking period, and from all

ovens which are not employed for the distillation of tar, etc., are collected in the usual way through the regular collector mains and passed to the usual condensing system. The gases and vapors given off from the ovens during the distillation of tar therein are collected separately and cooled to recover the distillate as well as tar constituents which may be carried by the gases and which are derived from the coking of the coal rather than the distillation and coking of the tar.

The present invention is of particular value for the distillation of coal tar produced at the by-product coke oven plant. Such tar, as ordinarily collected, contains a small percentage of water. Instead of introducing the wet tar into the coke oven to distill it, it may be first dehydrated and the dehydrated tar then introduced into the coke oven to effect its distillation. Instead of distilling tar in the coke oven, the tar can be partly distilled in a separate still and the resulting pitch introduced into the coke oven and there further distilled and coked. Other coke-forming residuum can be similarly introduced into the coke oven and there distilled and coked.

The amount of tar produced at a by-product coke oven plant varies somewhat with the kind of coal coked and the conditions of operation of the coke oven plant. It may be, for example, around eight to ten gallons of tar per ton of coal coked which represents around four to five percent by weight of the coal charged. When the tar is partly distilled and only the resulting pitch introduced into the coke oven for further distillation and coking, the pitch will represent a correspondingly smaller percentage by weight of the initial coal charge.

In carrying out the process, the tar or pitch is introduced into the top of the coke oven after the coke has formed therein and preferably near the end of the coking operation. After the coke is formed, the top of the coke and the top arch of the oven are incandescent and when tar is introduced in regulated amount into the top of the oven it is rapidly distilled and the residue coked. Similarly when pitch is introduced into the top of the incandescent oven it is rapidly distilled and coked. The period during which tar or pitch is introduced can be varied with the amount of tar or pitch to be distilled and coked, the rate of introduction, etc.

The tar or pitch is preferably introduced at a number of places so as to distribute it over the incandescent coke. It can be introduced in the form of small streams or by spraying the same through suitable spray nozzles or other devices for breaking up the tar or pitch and distributing it in the top of the coke oven and over the incandescent

coke therein. The tar or pitch will be heated by direct contact with the hot gases escaping through the top of the oven, by direct contact with the coke and by radiation from the incandescent top walls of the oven. The coking of the pitch produces not only coke but also gas in considerable amount. This gas, together with the gas given off from the coal will assist in sweeping the vapors from the distillation out of the oven and into the separate vapor main. If a larger amount of tar is introduced it may spread out in the form of a film over the coke and may run down through the coke charge to a greater or less extent. The introduction of an excessive amount of tar or pitch should in general be avoided.

In order to collect the distillate from the particular ovens employed for the distillation, I provide a separate vapor main into which the gases and vapors are passed during the distillation period so that they do not enter the ordinary gas main containing the ordinary tar laden gases. In a by-product coke oven plant provided with rich and lean gas mains for separately collecting rich and lean gases, one of the two mains can be employed in carrying out the present process. In that case, the lean gas main, for example, will be connected to the ovens in which the distillation of tar is being carried out and during the periods of such distillation so that the distillate will be separately collected. The gases from the other ovens and the gases during the early period of coking when distillation is not carried out will be collected in the other main and separately passed to the condensing system connected thereto. The distillate from the ovens employed for the distillation, together with the gases from such ovens given off during the distillation, will pass through the vapor main to a condensing system. The gases may be cooled to a greater or less extent in the vapor main and further cooled in the condensing system to recover either a total condensate or heavier and lighter condensates by fractional condensation.

The distillates produced by the present distillation process will be recovered in admixture with tar constituents carried by the gases given off from the coal. These gases will be relatively "lean" gases and the tar constituents which they contain will be of relatively high gravity. These tar constituents will be recovered on cooling the gases and vapors at the same time that the distillate from the distillation of the tar or pitch is cooled and condensed. The composite condensate recovered from the present process will be of a distinctive character.

If the gases and vapors coming from the ovens and resulting from the distillation are directly cooled, the condensates will be tarry oils containing more or less tar constituents,

including heavier pitch constituents. By subjecting the gases and vapors while at a high temperature to a suitable cleaning operation, as by a hot pitch scrubber or by an electrical precipitator at a high temperature, the gases and vapors can be cleaned and freed from heavier pitch constituents and the cleaned gases can then be cooled to recover clean marketable oils therefrom, such as creosote oils, or creosote and tar acid oils, etc.

The distillation of tar, etc., according to the present invention can be combined with the ordinary operation of a by-product coke oven plant by providing for the introduction of the tar, pitch or residuum during a suitable portion of the coking period and by providing for the separate withdrawal of the gases and vapors during the distillation. The distillation can be carried out in all of the individual ovens of a battery, by providing for the introduction of tar, etc., during a selected later portion of the coking period, or a part only of the ovens can be employed for the distillation. A smaller number of ovens can be employed and a relatively much larger amount of tar distilled in each oven, in which case a larger proportion of pitch coke will be contained in the composite coke product at the end of the coking operation.

The coke produced from the distillation of the tar and the coking of the resulting pitch will be combined intimately with the coke produced from the coking of the coal. If the coking of the pitch takes place only in the upper part of the oven, the composite coke, comprising coal coke and pitch coke, will be contained only in the upper part of the coke charge. If the tar or pitch runs down to lower levels before it is distilled and coked, the pitch coke may be distributed throughout a greater portion of the coal coke.

The invention will be further described in connection with the accompanying drawings which illustrate certain embodiments of the apparatus of the invention which are adapted for the carrying out of the process of the invention, but it is intended and will be understood that the invention is not limited thereto.

Fig. 1 is a plan view of a coke oven battery equipped for carrying out this invention;

Fig. 2 is a longitudinal section through one of the ovens of the battery;

Fig. 3 is a section along the line 3—3 of Fig. 2;

Fig. 4 is a detail in vertical section of Fig. 2; and

Figs. 5 and 6 are a plan view and elevation respectively of a modified form of apparatus.

Instead of providing only a single col-

lector main for collecting all of the gases from all of the ovens, or instead of providing two mains for separately collecting rich and lean gases, the apparatus shown in Figs. 1 and 2 provides both for the separate drawing off of rich and lean gases and the separate drawing off of the vapors and admixed gases from the distillation.

In Figs. 1 and 2 of the drawings the coke ovens 5 of the battery are connected through uptake pipes 6 and goose-necks 7 with three collector mains 8, 9 and 10. The collector main 8 is for rich gases, the collector main 9 for lean gases, and the main 10 is a vapor main for the collection of vapors resulting from the distillation of tar or pitch within the coke ovens. Each oven is connected with each of the mains through an uptake pipe 6 and a goose-neck 7. Valves 8', 9' and 10' are provided to direct the flow of gases and vapors from each of the ovens to each of the mains, as desired. The ovens are ordinarily charged in rotation so that the valves will ordinarily be manipulated in rotation to direct the gases and vapors from corresponding periods of the coking operation in each of the ovens to the same collector main.

The ovens are charged with coal through the openings 12. The coal is coked in the ordinary manner and the coke produced is represented at 13. Flues for heating the ovens are shown at 14. Regenerators 15 alternately are heated by the products of combustion and heat the air used to burn the gases in the well-known manner.

The gases in the gas collector mains 8 and 9 are cooled in any usual manner, as by ammonia liquor sprays. Tar and ammonia liquor are drawn off from these mains into the decanters 16' and 17'. The tar is separately collected in the tanks 16 and 17. The gases from the collector mains are further cooled in the condensers 18 and 19 to separate tarry oils. Tarry oils and ammonia liquor are drawn off from the condensers into the decanters 20' and 21'. The tarry oils are separately collected in the storage tanks 20 and 21. The tar and tarry oils thus obtained may be separately distilled in the ovens or the contents of all the tanks 16, 17, 20 and 21 may be pumped by the pumps 22 to the tar storage tank 24, and this total tar distilled in the ovens.

The ovens are charged with coal in the usual way and the coking may be carried on as usual. In those ovens in which the tar or pitch is to be distilled, after the coking has proceeded to a point where a large part of the volatile matter contained in the coal has been distilled off, the tar or pitch to be distilled is delivered to these ovens. This may be the tar from the tank 24. It may be supplied to the ovens through the pipes 27, which are connected with the tank 24 by

means of the pump 28 and lines 29. Tar or pitch from some other source than the tank 24 may be supplied to the ovens through the line 30. Any suitable means for supplying tar to the ovens may be employed. The portion of the tar supply pipe that passes through the walls or tops of the ovens is made removable so that it may be withdrawn when not in use, in order to give clearance to the coke pusher and coal leveller in discharging and charging the oven, and to avoid destruction by the heat of the oven when no tar is passing through it. For this purpose the pipes 27 are connected with the supply pipes 29 through toggle joints 27'. When not used for spraying, the pipes 27 may be removed from the oven as indicated in dotted lines in Fig. 2, and they may be doubled up and laid flat upon the top of the ovens. After using they are preferably blown with a fluid, such as steam, to remove all tar or pitch in order to prevent coking of tar or pitch in the pipes and stoppage of the pipes while not in use. After the pipes 27 have been removed from the ovens, the holes through which they enter the ovens are plugged up in any suitable manner to prevent the escape of gases from the ovens and the entrance of air into the ovens. That portion of the pipes 27 which is exposed to great heat may be coated with a protective refractory coating.

The tar is fed to the ovens preferably near the end of the coking operation in each oven. The coke is discharged through the door 31. All or only a portion of the ovens of the battery may be employed for the tar or pitch distillation. The vapors resulting from the distillation of the tar or pitch pass up through the uptake pipes 6 and goose-necks 7 of the selected ovens into the vapor main 10. Connection between each of the ovens and the vapor main 10 through the uptake pipes and goose-necks is controlled by the valves 10'. The uptake pipes and goose-necks leading to this vapor main 10 are advantageously insulated as indicated at 6'. This main 10 may be equipped with spray means for cooling the gases. Distillate condensing within the vapor main is drawn off into the collector tank or decanter located at 35 and any uncondensed vapors passed to the condensers 36.

The condensers 36 are here shown as direct condensers. The distillate together with the ammonia liquor which is drawn off from the condensers is collected in the decanter 37, and from there the oils are separately collected in the distillate storage tank 38. Distillate from the condensers 36 may be combined with the distillate oils from the vapor main 10, collected in the tank 35, or the two fractions may be kept separate. If a total distillate is desired the condensate from the main 10 together with any ammoni-

nia liquor which may be present is collected in the tank 35 and pumped from there by the pump 39 through the line 40 to the decanter 37, and there mixed with oils and ammonia liquor from the condensers. This total distillate is then separately collected in the tank 38.

The gases from the condensers 18, 19 and 36 pass through the exhausters 41, 42 and 43 and thence to means for the recovery of ammonia, etc.

Figs. 5 and 6 show a modified type of apparatus having a single collector main of the usual kind and having a separate vapor main located at the back end of the coke oven battery or block. The coke ovens 50 are of the same general type as that shown in the preceding figures. Each of the ovens of the battery is provided with the usual uptake pipe 51 and gas collector main 52 and those ovens in which tar or pitch is to be distilled are provided with a second uptake pipe 53 at the rear of the ovens. This uptake pipe connects with a vapor main 54. Valves are provided at 55 and 56 for directing the flow of the gas so that during the period in which tar or pitch is to be distilled, the gases and vapors will pass to the vapor main 54 and during the remainder of the coking operation the gases will pass to the gas collector main 52.

The tar or pitch is supplied through pipes 57 similar to the means shown in connection with the preceding figures. The valve 55 is closed and the valve 56 is opened while the tar or pitch is sprayed into the ovens. The gases resulting from the distillation of the coal during the period in which the tar or pitch is distilled pass off of the oven through the vapor main 54 together with gases and vapors resulting from the distillation of the tar or pitch.

According to the plan shown in Fig. 5, only a portion of the ovens of the battery are connected with the vapor main. Only those ovens connected with the vapor main are employed for distilling tar or pitch. The gases and vapors resulting from this distillation are collected in the vapor main and pass from the main to a separate condensing system which is here shown as a single direct condenser 58. From the condenser the gases pass through the exhauster 59 to means for the recovery of ammonia, light oils, etc.

The vapor main 54 is provided with sprays 60 through which ammonia liquor is sprayed into the gases and vapors passing through the vapor main so that the gases may be cooled to a regulated extent within the vapor main to separate higher boiling distillate.

The resulting partially cooled gases then pass to the condensers 58 where further cooling is effected and further distillate is

separated from the gases. The ammonia liquor and distillate from the vapor main 54 are drawn off into the decanter 61. The distillate is then separately collected into the storage tank 62. Distillate and ammonia liquor from the condenser 58 are drawn off into the decanter 63. From the decanter the distillate is separately collected in the storage tank 64.

10 The gases coming from the ovens connected with the vapor main 54 during periods in which there is no distillation of tar or pitch in these ovens and also the gases from those ovens not connected with this

15 vapor main are collected in the gas collector main 52 and treated in the usual manner. They may be sprayed in the collector main with ammonia liquor or they may be cooled by flushing the main with a mixture of tar and ammonia liquor. The partially cooled gases pass through the cross-over main 70 to the condensing system 71 and thence through the exhauster 72 to means for the recovery of ammonia and light oils.

20 25 The tar or pitch to be distilled is supplied to the ovens from any suitable source 73.

In carrying out the invention the ovens employed for the distillation of tar or pitch are connected with a vapor main and also with one or more gas collector mains. A single gas collector main may be employed with apparatus such as that shown in Figs. 1 and 2 and more than one gas main may be 30 35 employed with apparatus such as that shown in Figs. 5 and 6. The gases and vapors passing through the vapor main may be cooled to separate higher boiling distillate from the gas in this main and then be further treated in a condensing system to separate additional distillate.

It will thus be seen that the present invention provides an improved process for distilling tar, pitch or residuum with direct 40 45 production of coke and of distillate in which the distillation and coking are carried out as a part of the same operation and as a part of the coking operation at a by-product coke oven plant. The coke ovens are themselves employed for the distillation so that the pitch coke produced from the distillation is combined with the coal coke and so that the distillate from the distillation is recovered in a separate gas handling and condensing system. With plants which are now provided with two separate gas collecting and condensing systems, the present process can be carried out with a minimum of alteration merely by providing for the introduction of the tar or pitch into the coke ovens during the selected later portion of the coking period, and with utilization of one of the gas collecting and condensing systems for collecting and cooling the vapors and 50 55 60 65 70 75 80 85 90 95 100 105 110 115 120 125 130 gases from the distillation to recover the

distillate therefrom. With plants which do not have two gas collecting and condensing systems, separate provision should be made for drawing off and cooling the vapors and gases from the tar distillation operation. The gases from the separate collecting and condensing systems will ordinarily be combined and passed to the same gas handling system for recovering ammonia, light oils, etc., therefrom.

I claim:

1. The method of distilling coke-forming hydrocarbons and of producing therefrom coke and distillates which comprises introducing a coke-forming hydrocarbon in limited amount into the incandescent upper portion of a coke oven containing a coal charge which has been at least partially coked therein, and thereby rapidly heating and distilling the hydrocarbon and coking the residue, withdrawing from the coke oven the gases and vapors given off during the distillation of the hydrocarbon therein separately from the gases and vapors given off during the coking of the coal prior to such distillation, and separately cooling the gases and vapors to recover condensable constituents therefrom.

2. The method of distilling pitch-containing hydrocarbons and of producing therefrom coke and distillates which comprises coking coal in a coke oven until coke has formed from a considerable part of the coal, withdrawing the gases and vapors given off from the coal during such coking and cooling the same to separate tar therefrom, introducing a pitch-containing hydrocarbon into the incandescent upper portion of the coke oven during a later portion of the coking of the coal therein and thereby rapidly heating and distilling the hydrocarbon, and coking the residue, separately withdrawing the gases and vapors given off during such distillation, and cooling the same to recover the distillate therefrom.

3. The method of distilling tar and producing therefrom coke and distillates which comprises charging coal to a coke oven and coking it therein, drawing off the gases and vapors given off during all but a later portion of the coking of the coal through at least one collector main and passing the same to a condensing system to recover tar therefrom, returning at least a part of the tar and introducing it in limited amount into the coke oven during the later portion of the coking of the coal therein thereby rapidly distilling the tar and coking the residue and separately drawing off the gases and vapors from the oven during such distillation of tar therein, separately cooling such gases and vapors, and separately recovering the distillate.

4. The method of distilling pitch and producing therefrom coke and distillates

which comprises charging coal to a coke oven and coking it therein, drawing off the gases and vapors given off during all but a later portion of the coking of the coal

5 through at least one collector main and passing the same to a condensing system and recovering tar therefrom, introducing pitch in limited amount into the coke oven during the later portion of the coking of the coal

10 therein thereby rapidly distilling the pitch and coking the residue and separately drawing off the gases and vapors from the oven during such distillation of pitch therein, separately cooling such gases and vapors,

15 and separately recovering distillate.

5. The method of distilling tar which comprises charging coal into a coke oven and heating the oven to coke the coal therein, introducing tar into the coke oven after

20 coke has formed in the incandescent upper portion of the oven before all of the coal has been converted to coke, distributing the tar over the incandescent upper portion of the coke to bring about rapid heating and

25 distillation thereof and coking of the residue, drawing off the gases and vapors from the oven during such distillation of coal and tar, collecting the same separately from gases and vapors given off from the coal

30 prior to the introduction of the tar, separately cooling them to condense distillate, and separately collecting the distillate.

6. The method of distilling pitch which comprises charging coal into a coke oven

35 and heating the oven to coke the coal therein, introducing pitch into the coke oven after coke has formed in the incandescent upper portion thereof before all of the coal has been converted to coke, distributing the

40 pitch over the incandescent upper portion of the coke to bring about rapid heating and distillation of the pitch and coking of the residue, drawing off the gases and vapors from the oven during such distillation of

45 coal and pitch, collecting the same separately from gases and vapors given off from the coal prior to the introduction of the pitch to the oven, separately cooling them to condense distillate, and separately collecting

50 the distillate.

In testimony whereof I affix my signature.

HENRY H. BAILEY.
